UNITED STATES PATENT OFFICE.

ERNST G. K. ANDERSON, OF EVANSTON, ILLINOIS, ASSIGNOR TO APPLETON ELECTRIC COMPANY, A CORPORATION OF ILLINOIS.

SPOT LAMP.

Application filed October 25, 1924. Serial No. 745,789.

This invention relates to improvements in spot lamps for automobiles, boats, and for other uses, and to improvements in a switch for controlling the lamp circuit thereon.

5 My improvements are shown as applied to a demountable lamp wherein the conductor cord which connects the lamp with a source of current is adapted to be wound on and unwound from a reel during its normal 60 operation as a trouble lamp, and is contained on the reel when the lamp is adjusted to its normal fixed position, and wherein the lamp circuit control switch is associated with a manipulating handle for the lamp when the 65 lamp is mounted on its support to swing the lamp in positions to direct the light rays therefrom.

A purpose of the invention is to provide a simple means by which the reel for the cord 20 can be readily placed in a structure which constitutes part of the lamp casing and which is so arranged that it may be readily applied to or disconnected from the lamp casing.

25 The object of the invention is to produce a novel switch mechanism for the lamp circuit which is constructed to adapt it to the peculiar relation of the spring rewinding reel and the supporting and enclosing casing 30 for the lamp and to conveniently associate it with the manipulating handle for the lamp.

In the drawings showing one embodiment of my invention,—

Figure 1 is a part rear elevation and part 35 section on the line 1—1 of Figure 2.

Figure 2 is a section on the line 2—2 of Figure 1.

Figure 3 is a transverse section on the line 3—3 of Figure 1.

40 Figure 4 is a fragmentary view illustrating the means for fixing the reflector to the lamp casing.

Figures 5, 6 and 7 are details of the lamp circuit switch embodying my invention.

45 As shown in the drawings 10 designates a sheet metal rearwardly coned casing which is open at its front end and in which the rewinding mechanism and switch is contained. 11 designates an interior reflector 50 which is attached at its forward flanged edge between the flanged open end of the casing, within a rolled open ring 12, and the edge of the usual crown lens 13. A spur 14 (Figure 4) of the reflector holds said reflector 55 from turning.

The cord receiving reel is located in the casing in rear of the reflector and between it and the rewinding spring 15, hereinafter more specifically described. The said spring is contained within a barrel 16 which comprises an end wall 17 and a peripheral wall 18. It is closed at its end remote from the reflector by a sheet metal plate 19 fixed to a radial flange 20 of the barrel by means of eyelets 21 (Figures 1 and 2). The inner 60 end of its spring 15 is fixed to a sleeve 22 disposed coaxial with the lamp, and is held from rotation by being extended inwardly through an opening in the center of the reflector and swaged over the margin of said 65 opening, as at 23. The front wall 17 of the barrel is formed with a bearing boss 17' in which the sleeve 22 closely fits. The outer turn of the spring is connected to the flange 70 of the barrel by means of a rivet 24, and the 75 barrel turns about said sleeve.

25 designates a part cylindrical shell in rear of the reflector which conforms generally to the rear surface of the reflector 11. It is formed at its rear end as an annular 80 flange or tube 27 concentric to the axis of the lamp and is fixed to the front flat side of the spring barrel to rotate therewith and thus cause the shell 25 to rotate with the spring 85 barrel, one part extending through openings 85 in and clinched over the other part. A spacer ring 28 is applied over the boss 17' to hold the shell 25 away from frictional contact with the reflector shell. The flange or tube 90 27 constitutes the bottom of the lamp cord reel; and the sides of said reel are formed by the shell 25 and the forward wall of the spring barrel.

Contained within said sleeve 22 is the usual socket 30 to receive the base 31 of the 95 lamp, ordinarily connected thereto by the known bayonet lock. A spring 32 is enclosed in the shell 30 and is compressible between the base of the lamp and an insulating washer 33 fixed to and within the 100 outer end of the shell 30, as by turned-in flange or burr 33', shown in Figure 2. Inwardly beyond said shell 30, and of larger diameter than the said latter shell, and closed against the end of the shell, is a 105 washer 36 made of insulating material.

38 designates a washer which is shown as made of cup shape, and is fitted over the forward end of a tubular insulating body or shaft 39, the latter extending backwardly 110

through a short hollow lug 40 that is fixed to the rear end of the casing 10. Said lug is also removably connected and clamped to the body or shaft 39 by means of a screw 41. The hollow lug 40 constitutes convenient manual means for manipulating the lamp to turn it on its universal joints.

Within the outer end of the hollow shaft 39 is a sleeve 42 which is exteriorly threaded for a portion of its length (Figures 5 and 6) for threaded engagement with the bore of said shaft. Said sleeve is formed at its outer end with an enlarged socketed portion 46, as shown in Figures 2, 5 and 6. Within 15 said sleeve 42 is mounted, for axial reciprocation, a pin 43. Said latter pin is provided at its outer end with a head 44 that normally bears against the central contact of the lamp base to close the lamp circuit. A 20 spring 45 disposed between said head 44 and the bottom of said socketed portion 46 of the sleeve 42 tends to hold the head 44 resiliently pressed against the center contact of the lamp base.

25 Said pin 43 is made an integral part of a fin 47 which extends a distance inwardly beyond said sleeve 42 and said fin is formed at its outer edge with double beveled surfaces 48 (Figures 5, 6 and 7). The said sleeve 42 is fixed to the insulating body or shaft 39 by the internal screw thread connection mentioned, but is unthreaded for rotational engagement in the cup or washer 38 and the insulating washers 33, 36, as 30 shown in Figure 2. Said unthreaded cylindric part of the sleeve 42 extends through and is in electric contact with a metal washer 49, between which and the washer 38 is clamped a conducting brush 50 that constitutes, with said washers 38, 49, the sleeve 42, the pin 43, and its head 44, part of the 35 path of current to the central contact of the lamp. Separation of said head from the lamp terminal base breaks this path, or opens 40 the lamp circuit.

45 51 designates a switch actuating rod which is mounted for rotation, but non-axial, movement in the hollow insulating shaft or body 39. The outer end of said pin 51 is formed 50 with fork arms 52 between which enters and slides the fin of the pin 47 (Figures 2 and 7). The rod 51 is threaded at its outer end 53 into a bushing 54 that is molded in a hollow plug 55 which is axially disposed 55 with respect to the insulating body or shaft 39. A locking bolt 56, having a slotted head 57, is also threaded into the inner end of said bushing 54 to bear at its outer end against the inner end of the rod 51 and thereby to lock said rod endwise fixed in the shaft or hollow body 39.

60 The said sleeve 42 is provided at its inner end with diametrically disposed V-shaped notches 60 into which fit the bevels 48 of the fin 47. When the bevels of said fin 47 oc-

cupy the deepest parts of the notches 60, the head 44 of the pin 43 is, by the spring 45, extended beyond the enlarged end of said sleeve, as shown in Figure 6. At this time said spring 45 holds the head 44 70 pressed against the lamp base terminal and closes the lamp circuit. Upon turning the rod 51, it acts, through the interlocking arms 52 and fin 47, to cause the bevels at the end of the fin 47 to ride outwardly on the inclined faces of the V-shaped notches 60, thereby withdrawing the pin 43 inwardly into the threaded sleeve 42 a distance to break contact between the head 44 and the central terminal of the lamp base. This withdrawal of the pin will continue until the beveled edge 48 of the pin 47 is brought into the plane of the inner end of said sleeve, and, by continued turning of the fin and pin, the said beveled edge of the fin will ride on the inner end face of the sleeve, whereby the parts will be locked in circuit-opening position. Preferably, shallower notches 64, angularly spaced from the notches 60 on the end face of said sleeve 42, are provided in order to hold the parts to prevent accidental closing of the lamp circuit.

90 The wires included in the cord C, and embodying the wires c, c' are, respectively, grounded to the spring casing and connected to a lug 65, which is fixed to the back plate 20 of the spring barrel, the conductor c being connected to the sleeve 42 through the means of the conducting brush 50 that is fastened to said lug 65 and is forked to embrace the unthreaded part of said sleeve 42.

95 Referring now to the universal mounting for connecting the lamp structure to a fixed support, the same is made as follows:

100 70, 70 designate the jaws of a bracket 105 which are adapted to be clamped over a support, as the wind shield frame of an automobile. Clamping pressure can be effected by a bolt 71 which extends through the ears of said jaws. Located between said jaws and clamped thereon by the bolt 71 are two arms 75 of a sleeve 76. Within said sleeve 110 is a pivot bolt 77. Said latter bolt extends through ears 78 of a fitting 79, which fitting terminates in a split sleeve 80, whose axis is at right angles to the axis of the pivot bolt 77. Extending laterally from and fastened in any suitable manner to the casing at its larger diameter is a hollow arm 82, the outer cylindrical end 83 of which extends into and is fitted within said split sleeve 80. The split sleeve 80 is riveted at 85 to a metal ring clasp 86 that extends around the split sleeve 80 and terminates in a box-like enclosure 87, within which nonrotatively fits a nut 88 115 threaded to receive a thumb screw 89. When said thumb screw is turned downwardly through the nut 88, which latter is held non-rotatively by its engagement with the enclosure 87, the force of the nut acts 120

and reacts on the split sleeve 80 and clasp 86 to close it against the cylindric extension 83 of the arm 82. This has the effect of locking the lamp structure from turning freely on the pivot, constituted by the parts 83 and 80, and will hold the lamp normally in position, while permitting it, by a moderate manual force to be turned in a vertical plane.

The conductor cable C leads from the reel 10 and outwardly through the hollow arm 82, and thence downwardly through an opening in one of the arms of the fitting 79 to a source of current. Said cable may be knotted at C'' to prevent stress occasioned by 15 pulling out the cable from being transmitted to the connections of the cable cords described. Said cable may also be protected exterior to the mounting by a flexible metal sheath 91.

20 By reference to Figure 2, it will be observed that the member 39 is connected, through the sleeve 42, the shoulder 46, washer 33 and internal spurs or flange 33' to the socket 30 so that thereby the lamp 31 can be focused in the axis of the reflector 11 by endwise movement of said member 39; and can be locked in proper focal adjustment 25 by the screw 41.

I claim as my invention:

30 1. In combination with a lamp structure embracing a sleeve to receive a lamp base, of a tubular body to the rear of said sleeve in axial alignment therewith, a guide sleeve fixed in said tubular body, a pin guided in said sleeve towards and from, and normally spring pressed toward, the lamp base terminal, and a pin actuating member rotatable

in said body and interlocked to and adapted by rotation thereof to withdraw said pin from said base terminal.

40 2. In combination with a lamp structure embracing a sleeve to receive a lamp base, of a tubular body to the rear of said sleeve in axial alignment therewith, a guide sleeve fixed in said tubular body, a pin guided in said sleeve towards and from, and normally spring pressed toward, the lamp base terminal, cam connection between said pin and the outer end of said sleeve, and means to rotate said pin and cooperating with said 45 cam connection to withdraw said pin from the lamp base terminal to open the lamp circuit.

50 3. In combination with a lamp structure including a sleeve to receive a lamp base, of a tubular body to the rear of said sleeve and in axial alignment therewith, a guide sleeve fixed to said tubular body, a spring pressed pin guide in said sleeve, said pin having theron a fin, said guide sleeve being provided at its rear end with V-shaped recesses to receive the edge of the fin, whereby rotation of the pin causes the fin to ride up the sides of said recesses and produce an axial movement of the pin, and an operating device for the pin mounted in said tubular body and interlocked with the pin so as to permit the pin to be rotated by the operating device while the pin is moving in the direction of its length.

55 70 In witness whereof I claim the foregoing as my invention, I hereunto append my signature this 14th day of October, 1924.

ERNST G. K. ANDERSON.
